OR D11,267 EX

NO. 11,267

JUNE 24, 1879

UNITED STATES PATENT OFFICE

GEORGE S. BARKENTIN, OF HARTFORD, ASSIGNOR TO P. & F. CORBIN, OF NEW BRITAIN, CONNECTICUT.

DESIGN FOR HINGES.

Specification forming part of Design No. **11,267**, dated June 24, 1879; application filed May 31, 1879.
[Term of patent 7 years.]

To all whom it may concern:

Be it known that I, GEORGE SLATER BARKENTIN, of the city of Hartford, in the county of Hartford and State of Connecticut, have originated and produced a new and original Design for Hinges, of which the following is a full, clear, and exact description, reference being had to the accompanying engraving, making part of this specification.

My design relates to the ornamentation of the leaves and knuckle or joint of the hinge; and consists of a narrow sunken panel, A, with dotted ground running parallel to and near the outer edge of the leaves and knuckle, within which is a row of quarterfoils in relief. The said panel is preferably intersected at the four corners by rosettes, which are drilled and countersunk, forming a support for the screw-head.

Below the upper and above the lower panel on the leaves of the hinge are the borders B B, formed of zigzag bands, each outer division of which incloses a pointed leaf crossed by horizontal and vertical incised lines, and each inner division inclosing a sunken leaflet. Between the borders B B are vertical flutes and rosettes, as shown. On each division of the

knuckle are conventional leaf-ornaments, as at C C, springing from a central lozenge, all in relief within a sunken panel.

I claim as my invention—

1. The design of a hinge, consisting of the ornamentation upon the face of the leaves and knuckle, substantially as shown and described.
2. In a hinge, the design of the narrow panel A, extending around the outer edge of the leaves and over the knuckle, and inclosing the row of quarterfoils in relief, substantially as shown and described.
3. In a hinge, the design of the borders B B, consisting of the zigzag bands, inclosing pointed leaves and sunken leaflets, together with the horizontal and vertical incised lines, substantially as shown and described.
4. In a hinge, the design of the knuckle, consisting of the conventional leaf-ornaments C C, placed in relief within a sunken panel, as shown and described.

Signed by me this 28th day of May, A. D. 1879.

GEORGE SLATER BARKENTIN.

Witnesses:

CHARLES PECK,
CHAS. F. CORBIN.
